PUMP

William John Gee, London, England, assignor to
 The Gee Pump Company Limited, London,
 England

Application February 4, 1936, Serial No. 62,317
 In Great Britain April 28, 1934

6 Claims. (Cl. 103—156)

I have filed applications in Great Britain on the 28th April, 1934; 27th June, 1934 and 25th October, 1934.

The present invention relates to improvements in pumps having a number of pistons working in parallel. One of the objects of the invention is to provide pumps of large capacity and comparatively small size, suitable for use, for instance, as oil pumps or deep well pumps. At present, deep well pumps usually have a very long stroke and a very small number of strokes per unit of time, and they are very bulky.

This object of increasing the capacity and reducing the size of the pump is, according to the invention, attained by providing a pump with a number, preferably a considerable number of pump compartments and corresponding working pistons, which work synchronously with a short stroke less than the diameter of the piston. The individual pump compartments work in parallel so that the rate of delivery of the pump equals the sum of the rates of delivery of the individual compartments. For the same number of strokes per minute the capacity of the pump will therefore be equal to that of an ordinary single piston pump of about the same size having a much longer stroke, whilst with an increased number of strokes per minute, which is rendered possible by the reduced length of the stroke, the delivery of the pump may be made higher than that of an ordinary single piston long stroke pump of about the same size.

According to one construction, the improved pump comprises a relatively long working cylinder divided axially into a number of compartments. A central rod operated by any suitable means, for instance, by an eccentric crank or the like acting upon one end of the rod, is fitted within each compartment of the working cylinder with a collar adapted to operate as a piston, there being therefore one collar or piston for each compartment into which the cylinder is divided.

A preferred construction, particularly suitable for mines, which facilitates assembly of the parts, is the following:—

A pump cylinder consists of one long cylinder in which the compartments are formed by discs separated and held at the required distance by cylinder liners, the whole being secured by a screwed cap at one end or by screwed members at both ends. The pistons working in the compartments are formed of plates mounted upon a common piston rod and separated by distance pieces or tubes, the whole being locked in posi-

tion by one or more screwed ends. The pump cylinder and the associated valve chambers and valves are mounted in a common tube of large diameter in such a manner that a suction conduit and a delivery conduit are formed in the tube on opposite sides of the pump cylinder, and alongside thereof. The arrangement may also be such that the pump cylinder is mounted in the centre of a tube of large diameter but in such a manner that two conduits formed in the tube on opposite sides of the pump and alongside thereof are each used both as a suction and a delivery conduit. The latter arrangement is particularly suitable for submerged mine pumps. Each compartment may have two ports in the side, one at each end of the compartment. These ports may be controlled by positively operated valves, and the valves may be slide valves, and act alternately as suction and delivery valves. The valve may receive a reciprocatory movement, for instance, in the axial movement of the pump or an oscillatory or rotary movement about an axis parallel to the axis of the pump. When using positively operated valves it is possible to operate all or say one half of the valves simultaneously and synchronously by a common operating member. Instead of using positively operated valves, automatic suction and delivery valves may be used and in that case the common cylinder may again be arranged in the centre of a common tube of large diameter, and conduits formed in the tube on opposite sides of the pump and alongside therewith may each be used alternately as a suction and delivery conduit. Such a construction is particularly suitable for deep well pumps, the liquid flowing then substantially in an axial direction through the common tube.

In all cases the pump may be made double acting in all the compartments by suitable arrangements of the ports and the valves.

In order to reduce vibration and hammer which are liable to occur at high speeds, resilient means are interposed according to the invention between the pistons working in the individual compartments and their drive so as to obtain a cushioning effect at each end of the stroke. For instance, the pistons are not rigidly mounted on the common rod, but are capable of a limited axial sliding movement thereon, and suitable spring washers are interposed between the pistons and the tubular distance pieces.

The invention also provides an improved and simplified gear for operating a number of pistons and associated valves from a common rotating

shaft. According to the invention, a piston rod carrying a number of pistons is operated from the strap of an eccentric mounted upon the rotating shaft, whilst two sets of valves associated with the pistons, are operated by a rocking lever and interposed links, the rocking lever receiving its oscillating movement from the strap of the eccentric.

According to one construction of the operating gear, an eccentric mounted upon a horizontal shaft is provided with a strap having a depending extension or arm to which is pivoted the connection rod of the pistons. Upon the same shaft is loosely mounted a three-armed rocking lever. In the middle position of the rocking lever, one arm is in the vertical position and the other two arms are in the horizontal position, the eccentric being then either in the top or the bottom dead centre. One of the horizontal arms is connected by a pair of links with one set of valves and the other horizontal arm is connected by a pair of links with another set of valves, the two sets of valves being arranged diametrically opposite with regard to the common cylinder of the pump. The vertical arm is connected by a transverse member with a rod extending vertically from the top of the strap. During rotation of the shaft the eccentric operates by means of the strap all the pistons, and the oscillation of the strap is transmitted by the upwardly extending rod to the rocking lever, whereby the two sets of valves are operated. In all the preferred constructions the pistons do not contain any valves and all the valves are arranged outside the compartments.

The improved gear has the advantage of great compactness. The part operating the valves is balanced and a very quick opening and closing movement is attained.

The accompanying drawings show by way of example three constructions embodying the features of the invention.

Fig. 1 is a sectional elevation on line I—I of Fig. 2 of a pump having positively operated slide valves.

Fig. 2 is a section on line II—II of Fig. 1.

Fig. 3 is a cross section on line III—III of Fig. 1.

Fig. 4 is a top view of Fig. 1.

Fig. 5 is a partial cross section on line V—V of Fig. 1.

Fig. 6 is a sectional elevation of a modified construction in which spring washers are interposed between the pistons and their drive.

Fig. 7 is a section on line VII—VII of Fig. 6.

Fig. 8 shows in sectional elevation a pump suitable for use in a mine, in which the valves are automatically operated.

Fig. 9 is a cross section on line IX—IX of Fig. 8.

Fig. 10 is a cross section on line X—X of Fig. 8.

Fig. 11 shows in sectional elevation, some parts being shown in view, a twin pump in which rotary positively operated valves are used.

Fig. 12 is a cross section on line XII—XII of Fig. 11.

Referring first to Figs. 1 to 5, 1 indicates a tubular outer casing closed at the lower end by a base plate 5 fixed to the casing 1 by bolts 8, and having a suction conduit 2 and a delivery conduit 3. The casing is closed at the top by means of a cover 6 fixed by means of bolts 7. The tubular casing 1 is divided by a transverse pump body 4 into two separate chambers 10 and 11, the chamber 10 communicating with the suction 2 and the chamber 11 communicating with the delivery 3. The pump body 4 has a cylindrical bore 12 in which four pump compartments 13, 14, 15 and

16 are formed by end discs 17, 18, 19 and 20 which are held at the required distance by cylindrical liners 9, 9, 9, 9 of the pump body 4. In the compartments 13, 14, 15 and 16 work four pistons 21 mounted upon a common piston rod 22 and held upon said rod at the required distance by tubular distance pieces or sleeves 23. Each compartment communicates with the chamber 10 by means of two suction ports 24 and 25 extending through the body 4 and liners 9 and also with the chamber 11 by two similar delivery ports 26 and 27, the pump being of the double-acting type. The top end of the piston rod 22 is screwed into a rod 28 guided vertically in a gland 29 of the cover 6. The suction ports 24, 25 are controlled by a common plate-shaped member 30 vertically guided upon the face of the pump body 4 in guide-ways 31, 31 fixed to the face of the pump body, said plate member 30 having ports 32 adapted to register with the section ports 24 and 25. In the middle position of the plate 30 the ports 32 register with the discs 17, 18, 19, 20 and when moved from this middle position in the one or the other direction, open adjacent suction ports. The delivery ports 26, 27 are controlled by a similar plate 33 guided in ways 34 and provided with discharge openings 35.

The pistons 21 and the valve plates 30 and 33 are operated from a common shaft 36 mounted in ball bearings 37, 38 carried by uprights 39, 40 fixed upon the cover 6 by bolts 7. Upon the shaft 36 are fixedly mounted two identical eccentrics 41, 41 having a common strap 42 which is pivotally connected by a bolt 43 with the upper end of the rod 28. Between the eccentrics 41 is loosely mounted upon the shaft 36 a three-armed lever 44, 45, 45. The middle arm 44 of this lever is slidably in a vertical bore 46 of a cylindrical pin 47 rotatably mounted in vertical extensions 48 of the strap 42. The arms 45, 45 of the three-armed lever 44, 45, 45 are connected by double links 49, 49, 50, 50 with rods 51, 52 which are vertically guided in glands 53, 54 of the cover, the rod 51 being connected with the plate 30 and the rod 52 being connected with plate 33. Upon rotation of the shaft 36 the rod 28 is reciprocating vertically by the eccentrics 41 and drives the four pistons 21. At the same time, the plate valves 30 and 33 are operated in opposite directions by the three-armed lever 44, 45, 45 which receives its movement from the eccentric strap arm 48, 48 through a cross member 47 and drives the valves by means of links 49, 50 and rods 51, 52.

It will be seen that by this mechanism the valves receive a very quick opening and closing movement.

The construction of the pump is very simple and the parts can be easily assembled. The construction is extremely compact particularly if compared with the usual well pumps having a single piston and a comparatively long stroke.

In order to reduce vibration and hammer which may occur at high speeds, resilient means may be interposed between the pistons working in the individual compartments and their drive so as to obtain a cushioning effect at each end of the stroke. A construction serving this purpose is shown in Figs. 6 and 7. In these figures 22 indicates a common piston rod, 21, 21 are pistons working in compartments 14, 15; 19 and 20 are end discs, and 23, 23, 23 are tubular distance members holding the pistons 21 apart. Between the tubular distance members 23 and the pistons 21 are interposed spring washers 56 through which the drive is transmitted.

Figs. 8, 9 and 10 illustrate a construction according to the invention in which automatic suction and delivery valves are used. In this construction a tubular outer casing 60 is integral with a pump body 61 having a cylindrical bore, the annular space between the casing 60 and the pump body 61 being closed at the lower end by an integral plate 62 and being closed at the top by an integral plate 63, and is divided by two longitudinal ribs 64, 64 into two chambers 65, 66. Each of these chambers alternately acts as a suction and a delivery conduit. The pump body 61 is closed at the top by a screwed-in cover 67 and at the bottom by a screwed-in cover 68. In the plate 62 are mounted automatic suction valves 69, five such valves being provided on either side. The lift of the valve is limited by stops 70 screwed into the outer casing. A perforated basket 71 is fixed by means of a bolt 72 to the bottom 63 of the pump body. A chamber 73 formed above the pump body communicates with a delivery pipe 74 screwed into the top of the chamber 73. In the chamber 73 are mounted delivery valves 75 having their seats in the plate 63. The lift of the delivery valves 75 is limited by stops 76 screwed into the top of the chamber 73. There are ten delivery valves. The chamber 73 is reinforced by ribs 77. In the pump body 61 are formed six pump compartments 78, 79, 80, 81, 82, 83 by means of end discs 84 and tubular liners 85. Each of the compartments has at the top ports 86 and at the bottom ports 87, the ports 87 communicating with the semi-annular chamber 66 and the ports 86 communicating with the semi-annular chamber 65. All these ports alternately act as suction and delivery ports. In the pump compartments 78-83 work pistons 88 which are mounted upon a common piston rod 89 and are held at the required distance by tubular distance pieces 90. The lowest piston 88 is held by a nut 91 upon the rod 89 and the top piston is held by a shoulder 92. The upper end of the piston rod 89 is guided in a gland 93 of the end disc 67.

The reciprocating of the piston rod 89 may be obtained in any suitable manner, for instance, by an eccentric drive. Upon reciprocation of the piston rod 89 the pistons move synchronously in their respective compartments. During the downward stroke liquid is drawn in through the ports 86 and the valves 69 of the chamber 65 and simultaneously liquid is delivered through the ports 87 into the chamber 66 and through the delivery valves 75 communicating with this chamber. During the upward stroke liquid is drawn in through the valves 69 into the chamber 66 and through the ports 87 and at the same time liquid is delivered above the piston through the ports 86 into the chamber 65 and through the delivery valve 76 communicating with that chamber.

It will be seen that in this construction, too, all the parts can be easily assembled and dismounted and that a very high capacity is obtained with a comparatively small size.

Figs. 11 and 12 show a construction embodying the features of the invention of a twin pump, each of the units having four compartments and both units being controlled by a common multiple rotary valve.

100 is a tubular outer casing having a suction conduit 101 and a delivery conduit 102. The casing is closed at the top by means of a cover 104, and is closed at the bottom by means of a base plate

105 fixed to the casing by bolts 106. The tubular casing 100 is divided by a transverse pump body 107 into two separate chambers 108 and 109 of which the chamber 108 communicates with the suction 101 and the chamber 109 communicates with the delivery 102. The pump body 107 has two cylindrical bores 110 and 111 which are divided each into four compartments 112 by means of end discs 113. The end discs are held at the required distance by cylindrical liners 114. Each compartment has two ports 115 and 116 and each of these ports alternately acts as suction and delivery port. The ports extend through the end discs. Each port is alternately brought into communication with the chamber 108 and 109 by means of a rotary valve member 117 mounted in a central bore 118 of the pump body 107. The central bore 118 communicates with the chambers 108 and 109 by means of lateral ports 119 and 120. The valve member 117 has recesses 121 and 122 adapted to establish communication between the ports 115, 116 and the ports 119, 120. Pistons 123 working in the pump compartments are mounted on two piston rods 124, 124 and are held at the required distance apart by cylindrical tubes 125, the lowest piston being held by nuts 126 and the top pistons being held axially by cylindrical sleeves 127. The two piston rods 124 are driven from a common shaft 128 which is mounted in ball bearings 129, 129 carried by the cover 103. The piston rods are driven by eccentrics 130, 130 mounted upon the shaft 128 at a phase angle of 90°. The common distributing valve 117 is driven from the shaft by bevel gears 131 and 132 at half the speed of the shaft 128.

It will be seen that in this construction too, all the parts can be easily assembled and dismounted and that the capacity of the pump is very high considering the size of the pump.

Whilst it is, of course, possible to use any suitable kind of pistons, some preferred piston constructions are indicated in the drawings.

I claim:

1. A pump having a plurality of tandem pumping units, comprising a cylinder body having a cylindrical bore, there being a chamber on each side of the cylinder body, a plurality of liners in the bore of the cylindrical body, a spacing disc between adjacent liners, a cylinder head at each end of the bore, the liners, discs and heads forming cylinders, there being ports connecting the ends of the cylinders with the chambers at the sides of the cylinder body, a piston rod, and a piston in each cylinder connected to the piston rod.

2. A pump having a plurality of tandem pumping units, comprising a cylinder body having a cylindrical bore, there being a chamber on each side of the cylinder body, a plurality of liners in the bore of the cylindrical body, a spacing disc between adjacent liners, a cylinder head at each end of the bore, the liners, discs and heads forming cylinders, there being ports connecting the ends of the cylinders with the chambers at the sides of the cylinder body, a piston rod, a piston in each cylinder on the piston rod, a spacing sleeve on the rod between adjacent pistons, and means for clamping the pistons and spacing sleeves on the piston rod.

3. A pump having a plurality of tandem pumping units, comprising a cylinder body having a cylindrical bore, there being a chamber on each side of the cylinder body, an inlet valve for each chamber, an outlet valve for each chamber, a plurality of liners in the bore of the cylinder body, a spacing disc between adjacent liners, a

cylinder head at each end of the bore, the liners, discs and heads forming cylinders, there being ports connecting the ends of the cylinders with the chambers at the sides of the cylinder body, 5 a piston rod, and a piston in each cylinder connected to the piston rod.

4. A pump having a plurality of tandem pumping units comprising a body having a cylindrical bore, a shell on the exterior of the body, there 10 being a chamber on each side of the body between the body and the shell, a plurality of liners in the bore of the cylinder body, a spacing disc between adjacent liners, a cylinder head at each end of the bore, the liners, discs and heads forming 15 cylinders, there being ports connecting the ends of the cylinders with the chambers at the sides of the cylinder body, a piston rod, and a piston in each cylinder connected to the piston rod.

5. A pump having a plurality of tandem pumping 20 units, comprising a cylinder body having a cylindrical bore, there being a chamber on each side of the cylinder body, a plurality of liners in the bore of the cylinder body, a spacing disc between adjacent liners, a cylinder head at each

end of the bore, the liners, discs and heads forming cylinders, there being ports connecting the ends of the cylinders with the chambers at the sides of the cylinder body, a piston rod, a piston in each cylinder on the piston rod, a spacing sleeve on the rod between adjacent pistons, resilient means between the pistons and adjacent spacing sleeves and means for clamping the pistons and spacing sleeves on the piston rod. 5

6. A pump having a plurality of tandem pumping 10 units, comprising a body having a cylindrical bore centrally thereof, there being a chamber in the body on each side of the bore, a plurality of liners in the bore, a spacing disc between adjacent liners, a cylinder head at each end of 15 the bore, the liners, discs and heads forming cylinders, there being ports connecting the ends of the cylinders with the chambers at the sides of the bore, a piston rod, a piston in each cylinder connected to the piston rod, an inlet valve for 20 each chamber, and an outlet valve for each chamber.

WILLIAM JOHN GEE.
